DOUBLE-PULL AUTOMATIC LOCK SLIDER

Frederick Ulrich, Jersey City, and Otto Scheuermann, Westfield, N. J., assignors to Conmar Products Corporation, Newark, N. J., a corporation of New Jersey

Application May 1, 1945, Serial No. 591,348

9 Claims. (Cl. 24—205.5)

1

This invention relates to an automatic lock slider for slide fasteners.

The invention is directed more particularly to an improved automatic lock slider of the so-called double-pull or double-acting type, such type comprising a lock slider having a pull device on each side thereof (front and rear) so that the locking member may be moved to unlocking position by operation of either pull device.

The prime object of our present invention centers about the provision of an improved double-acting automatic lock slider for slide fasteners which is simple in construction, rugged in character, positive in action and capable of rapid manufacturing and assembling operations.

To the accomplishment of this main object and such other objects as may hereinafter appear, our invention relates to a double-pull or double-acting automatic locking slider for slide fasteners as sought to be defined in the appended claims and as described in the following specification taken together with the annexed drawings in which:

Fig. 1 is a front plan view of the slider embodying the principles of the present invention;

Fig. 2 is a cross-sectional view taken in the planes of the broken line 2—2 of Fig. 1;

Fig. 3 is a rear plan view thereof, but showing the rear pull in a position different from that of Fig. 2;

Fig. 4 is a fragmentary section taken in the plane of the line 4—4 of Fig. 2;

Fig. 5 is a detail showing the locking member of the slider of Figs. 1 to 3 in an end view;

Fig. 6 is a view explanatory of the assembly of the slider body and locking member; and

Fig. 7 and Fig. 8 are views illustrating the actuation of the slider by means of the front pull and rear pull, respectively.

Referring now more in detail to the drawings and having reference first to Figs. 1 to 3 thereof, the double-pull or double-acting automatic lock slider of the present invention comprises a slider body generally designated as B having front and rear wings 10 and 12 joined at their upper ends by a neck or so-called "diamond" 14, a U-shaped locking member generally designated as L longitudinally straddling the wings of the slider and fulcrumed to the slider body at the point f, the said locking member L being active automatically for locking the slider to the elements illustrated by the fastener element e (Fig. 2) of slide fastener stringers with which the slider is used, a pull device p on one side of the slider operative on one branch and a pull device p' on the other

2

side of the slider operative on the other branch of the said U-shaped locking member L for moving the locking member about its said fulcrum f to unlocking position.

5 The slider body B, besides its conventional shape by which the front and rear wings 10 and 12 and the connecting neck 14 define interiorly a Y-shaped slider channel for the mating slide fastener stringers and besides having an orifice 16 in its front wing for the locking tooth of the locking member L, is in the preferred embodiment of the present invention formed at its neck 14 with a medially arranged external recess 18; and the rear wing 12 of the slider body is formed with a 10 lower lug 20 and two upper spaced lugs 22 adapted to receive and upon which is mounted a closure cap 24 which latter may be secured onto these lugs in any desired way. The front wing 10 is also preferably provided with the outwardly extending spaced lugs 26, 26 to serve as the bearings for the fulcrum f. In the form of the invention exemplified, the body B is a die cast unit.

The locking member L, which in the form selected for illustration is a sheet metal piece, is 15 generally U-shaped and comprises a front branch 28, a rear branch 30 and a connecting piece 32, one of these branches such as the front branch 28 being formed with a locking tooth 34 which protrudes through the front wing orifice 16 into 20 the slider channel for locking engagement with a slide fastener element such as the element e (see Fig. 2). As heretofore stated, the U-shaped locking member L is fulcrumed at one point on the slider body and this fulcrum is preferably taken 25 at the neck of the slider. The locking member L forms a rigid part or piece pivoted at the fulcrum f to the spaced lugs 26, 26 projecting from the neck proper 14. The locking member L is fulcrumed to the slider body B by means of the pivot 30 pin 36 which is received in aligned bearing holes 35 in the lugs 26, 26 and a bore in the locking member. This latter is best shown in Figs. 1 and 2 of the drawings from which it will be also seen that the connecting piece 32 of the locking member L is thereby lodged in the recess 18 formed at the top of the neck.

The locking member L is spring actuated to 40 automatically locked condition. The spring may comprise a flat or leaf spring member 38 which is 45 loosely inserted into a seat 40 defined by the lugs 20 and 22 on the rear slider wing, the said spring being active on the rear branch 30 of the locking member L and held in place thereby. In Fig. 2 this spring is shown as being active on the rear branch of the locking member for moving the

locking member about its fulcrum *f* to slider locking position.

The front and rear pull devices *p* and *p'* are each slidably movable in slider opening and closing directions for positively moving the locking member in each instance to its unlocking position. This is preferably accomplished by the provision in each of the branches 28 and 30 of the locking member *L* of oppositely directed cam faces against which the trunnions of the pull devices are active in their slider opening and closing operations. Thus the front branch 28 of the locking member is formed with the oppositely directed cam faces 42 and 44, and the trunnions (or cross bar) 46 of the pull device *p* are lodged between these cam faces and the front slider wing 10. The rear branch 30 of the locking member is formed with the oppositely directed cam faces 48 and 50; and the trunnions (or cross bar) 52 of the pull device *p'* are lodged between these cam faces and the slider cap 24, the slider cap being formed with suitable apertures 54 for these trunnions. With this recited construction, it will be evident that slidable movement of the pull *p* in either the opening or closing direction and similar slidable movement of the pull device *p'* in either the opening or closing direction will positively move the locking member *L* about its fulcrum or pivot against the action of the spring 38 to unlocking position.

This operation of the slider will be clear from a consideration of Figs. 7 and 8 of the drawings. In moving the slider by means of the front pull *p* either in the opening direction (full line position of the pull) or in the closing direction (the dot and dash line position of the pull), the pull operates upon the respective cam surfaces 42 and 44 of the locking member and cams the locking member out of the locking position of Fig. 2 into the unlocking position of Fig. 7 and moves the locking tooth 34 out of engagement with the slide fastener elements. This is accomplished against the action of the spring 38 acting on the rear branch 30 of the locking member. As soon as the front pull is released, the spring resumes its de-energized shape and moves the locking member about its fulcrum to its locking position. In Fig. 8 the slider is shown actuated by the rear pull *p'*. The full line position of the pull illustrates the action of the pull on the slider in opening direction and the dot and dash line position illustrates the action of the pull on the slider in closing direction, the pull operating upon the respective cam surfaces 48 and 50 to cam the locking member out of the locking position of Fig. 2 into the unlocking position of Fig. 8. Again when the rear pull *p'* is released, the spring 38 acts to move the locking member *L* back to the locking position shown in Fig. 2.

Fig. 6 is intended to illustrate the simple mode of assembling the slider body *B* and the locking member *L*. The locking member *L* is moved into straddling position longitudinally over the slider body *B* from a starting position I through an assumed intermediate position II through a final position III. The front pull *p* may be inserted into position as the locking member *L* is moved from position II to position III. The rear pull *p'* is assembled to the slider body before the attachment to the body of the cap 24. Where the front pull is provided with open end trunnions (instead of closed end trunnions to form a cross bar as shown in Fig. 3), the front pull may, of course, be attached in position after the locking member has been assembled to the slider body.

The structure, the mode of operation, the manner of assembling the parts, and the many advantages from manufacturing and use standpoints of the automatic lock slider of the present invention will in the main be fully apparent from the above detailed description thereof. For a double-acting slider the device is simple in construction. The locking member *L* and the slider body *B* may be quickly assembled after the manner shown in Fig. 6 of the drawings. The rear pull and cap may then be quickly attached and the slider thus completed. Operation of either the front pull or the rear pull in either the opening or closing direction of the slider effects the positive movement of the locking member to its unlocking position. Release of either pull causes the locking member to be automatically moved to its locking position. The device is rugged in character and positive in action. The parts are, moreover, so inter-nested as to produce a desirably small slider unit.

It will be apparent that many changes may be made in the construction described without departing from the principle of the invention as defined in the following claims.

25 We claim:

1. A double-pull automatic lock slider for slide fasteners comprising a slider body having front and rear wings joined at their upper ends by a neck, a U-shaped locking member longitudinally straddling the wings of the slider and fulcrumed to the slider at its neck, a spring active on the rear branch of said U-shaped locking member for moving the same about its said fulcrum to locking position, and a pull on one side of said slider operative on one branch and a pull on the other side of said slider operative on the other branch of said U-shaped locking member for moving the same about its said fulcrum against the action of said spring to unlocking position.

40 2. A double-pull automatic lock slider for slide fasteners comprising a slider body having front and rear wings joined at their upper ends by a neck, a U-shaped locking member longitudinally straddling the wings of the slider and fulcrumed to the slider at its neck, means active on said locking member for moving the same about its said fulcrum to locking position, a pull on one side of said slider slidably movable in slider opening and closing directions for positively moving one branch, and a pull on the other side of said slider also slidably movable in slider opening and closing directions for positively moving the other branch, of said U-shaped locking member for moving the latter about its said fulcrum to unlocking position.

3. A double-pull automatic lock slider for slide fasteners comprising a slider body having front and rear wings joined at their upper ends by a neck, a U-shaped locking member longitudinally straddling the wings of the slider and fulcrumed to the slider at its neck, a spring active on the rear branch of said U-shaped locking member for moving the same about its said fulcrum to locking position, a pull on one side of said slider slidably movable in slider opening and closing directions for positively moving one branch, and a pull on the other side of said slider also slidably movable in slider opening and closing directions for positively moving the other branch, of said U-shaped locking member for moving the latter about its said fulcrum to unlocking position.

4. The double-pull automatic lock slider of claim 2 in which each branch of the U-shaped locking member is formed with oppositely directed cam faces against which said pulls are

75 rected

active in their slider opening and closing operations.

5. A double-pull automatic lock slider for slide fasteners comprising a slider body having front and rear wings joined at their upper ends by a neck, a rigid U-shaped locking member longitudinally straddling the wings of the slider and fulcrumed at one point to the slider, means active on said locking member for moving the same about its said fulcrum to locking position, and a pull on one side of said slider operative on one branch and a pull on the other side of said slider operative on the other branch of said U-shaped locking member for moving the same about its said fulcrum to unlocking position.

6. The double-pull automatic lock slider of claim 5 in which the said neck is provided with an external recess at its top and the piece connecting the branches of the U-shaped locking member is lodged in said recess.

7. A double-pull automatic lock slider for slide fasteners comprising a slider body having front and rear wings joined at their upper ends by a neck, a U-shaped locking member longitudinally straddling the wings of the slider and fulcrumed at one point to the slider, a cap secured to the rear wing of the slider body and housing the rear branch of said locking member, means active on said locking member for moving the same about its said fulcrum to locking position, a pull on the front side of said slider active between the front wing and the front branch of said locking member for moving the locking member about its said fulcrum to unlocking position, and a pull on the rear side of said slider active between said cap and the rear branch of said locking member for moving the locking member about its said fulcrum to unlocking position.

8. The double-pull automatic lock slider of claim 7 in which each branch of the U-shaped locking member is formed with oppositely directed cam faces against which said pulls are active.

9. A double-pull automatic lock slider for slide fasteners comprising a slider body having front and rear wings joined at their upper ends by a neck, said neck having an external recess at its top, a U-shaped locking member longitudinally straddling the wings of the slider with its connecting piece lodged in the recess of said neck fulcrumed to the slider at its neck, a cap secured to the rear wing of the slider body and housing the rear branch of said locking member, a spring active on the rear branch of said locking member for moving the locking member about its said fulcrum to locking position, a pull on the front side of said slider slidably active between the front wing and the front branch of said locking member for positively moving the locking member about its said fulcrum to unlocking position, and a pull on the rear side of said slider slidably active between said cap and the rear branch of said locking member for positively moving the locking member about its said fulcrum to unlocking position.
